PRESSER BAR CONTROL FOR SEWING MACHINES

Filed March 26, 1948

UNITED STATES PATENT OFFICE

2,534,651

PRESSER BAR CONTROL FOR SEWING MACHINES

Ralph L. Abos, Laurence M. Stanfield, and Robert B. Myers, Los Angeles, Calif., assignors to Revco Products, Whittier, Calif., a corporation of California

Application March 26, 1948, Serial No. 17,265

19 Claims. (Cl. 112—236)

1

This invention relates to means for varying the pressure conventionally applied upon the presser foot members of sewing machines.

Sewing machines are commonly provided with a hollow head in which is mounted a needle bar and a presser foot bar, both of which extend downward below the head, the presser bar being associated with a spring whose adjustment may be regulated to vary its compression and thereby vary the pressure which the presser foot places upon the fabric being stitched.

It is an object of the present invention to provide a simple and very quickly operable means adapted not only to release the compression upon the presser bar spring so that darning may be readily effected, but it is also an object of the invention to provide such a structure by means of which any intermediate degree of compression desired in the presser bar spring may be obtained and by which any such intermediate compression may be instantly produced.

A further object of the invention is to provide such a compression adjusting device which shall be very simple in construction and inexpensive to manufacture, in addition to providing the mentioned advantage of being quickly adjusted or released.

Other objects of the invention will become apparent to those skilled in this art upon reference to the following specification and the accompanying drawing wherein certain embodiments of the invention are presented by way of exemplification.

In the drawing:

Fig. 1 is an end elevation of a conventional sewing machine head equipped with a pressure control device of this invention;

Fig. 2 is a vertical section approximately as taken on the line 2—2 of Fig. 1, the parts being in spring-releasing position;

Fig. 3 is a vertical section similar to that of Fig. 2 showing the parts in the position for retaining the desired compression upon the spring of the presser bar;

Fig. 4 is a view taken from the line 4—4 of Fig. 3, portions being broken away to facilitate the showing;

Fig. 5 is a fragmentary vertical section on an enlarged scale showing a portion of the structure of Fig. 3;

Fig. 6 is a fragmentary vertical section similar to that of Fig. 5 and illustrating a modification;

Fig. 7 is a vertical section showing the parts in Fig. 6 in released relationship; and

Fig. 8 is a fragmentary vertical section of a further modification.

2

The drawing illustrates a conventional sewing machine head 10 having the usual cavity 11 which may be enclosed by a removable, conventional cover plate 12. Within the cavity 11 there is disposed a conventional needle bar 13, whose lower end projects from the head 10 and carries a needle 14, the usual presser bar 15 being disposed behind the needle bar 13 and also projecting below the head 10 with its lower end carrying a conventional presser foot 16. Upon the presser bar 15 and within the cavity 11 there is pinned or otherwise secured a collar 17 upon which bears the lower end of a conventional, coiled compression spring 18 disposed about the upper portion of the presser bar 15. The upper end of the spring 18 in the form shown bears against the underside of a washer-like member 19 slidable on the bar 15.

The present improvement comprises a vertically slidable sleeve 20 constituting an adjusting stem having a bore 20a whose lower end telescopically receives the upper end of the presser bar 15 and integrally or frictionally connects with the washer member 19 to control the spring 18. The top of the sleeve 20 is provided with a knob 21 which is adapted to be engaged by the operator to depress the sleeve 20 as required. The sleeve 20 is mounted in a headed screw 22 having a short threaded shank 23 adapted to be received in corresponding threads in the upper end of the machine head 10, the head of the screw 22 overhanging the top of the machine head 10 and being adapted to be turned down tight thereagainst to prevent dislodgment. The head of the screw 22 is preferably knurled to facilitate such tightening, and it is internally provided at its top with a countersink 22a which receives an upwardly acting coil spring 24 disposed about the sleeve 20 and bearing upon the underside of a friction lock arm 25 apertured to receive the sleeve 20. One end of the lock arm 25 is free and extends outward to present a finger rest 26 for the machine operator.

In the preferred form of the invention illustrated in Figs. 1 to 5, the lock arm 25 is produced from hardened steel and its inner end is disposed in the countersink 22a and retained therein by means of an integral short tongue 27 which extends into a slot 28 formed in one side of the head of the screw 22, the slot 28 leading outward from the countersink 22a, as best seen in Fig. 5. A preferably circular aperture 30 is provided in the lock arm 25 to receive the stem or sleeve 20. When the lock arm 25 is in locking position, it is tilted at an angle as illustrated in Figs. 3 and 5 so that it presents to the sleeve 20

a sharp locking shoulder 32 at the lowermost edge of the aperture 30, this shoulder being adapted to bind upon the adjacent side portion of the sleeve 20 to retain the sleeve 20 against upward movement under the biasing influence of the spring 18. The opposite and uppermost edge of the aperture 30 serves as a back wall to hold the opposite side of the sleeve 20 and insure proper retaining engagement of the shoulder 32.

In the form of the invention shown in Figs. 6 and 7, the friction lock arm 25 is produced from spring material and is provided with a spring bend 34 whose normal set is such as to maintain the relationship shown in Fig. 6. The spring bend 34 is an auxiliary to the spring 24. Here, the lower end of the friction lock arm 25 underlies the head of the screw 22 and is apertured to provide an eye 38 through which the short threaded shank 23 is passed. In this instance the eye 38 serves as a washer between the head of the screw 22 and the machine head 10. If desired, the spring 24 may be omitted in this form, as indicated in Fig. 7, and the resilience in the spring bend 34 between the eye 38 and the lock arm 25 relied upon both for the necessary spring action and for such relative movement of the walls of the aperture 30 with respect to the sleeve 20 as is required.

The modification of Fig. 8 is similar to that of Fig. 6, but here the lower end 35 of the lock arm 25 is bifurcated to provide fingers 40 which are received in an exteriorly located annular groove 42 in the head of the screw 22. The coil spring 24 serves to assist the spring bend 34, as in the case of the form of Fig. 6. However, the friction lock arm 25 and the bend 34 of this form may be rigid and without resilience. In this case, play of the fingers 40 in the annular groove 42 will be provided sufficient to accommodate the necessary movements between locking and releasing positions.

Figs. 5, 6, 7 and 8 are used also to illustrate that the threaded shank 23 of the screw 22 may be very short, it being necessary merely that it be long enough to retain the screw 22 bound in operative position.

In operating the releasing and adjusting mechanism of this invention, the operator presses upon the knob 21 when it is desired to apply pressure to the presser bar spring 18 or to increase the compression. Under such conditions, the sleeve 20 slides readily through the aperture 30 and past the binding shoulder 32. When movement of the knob 21 ceases, the shoulder 32 promptly binds upon the adjacent side portion of the sleeve 20 and locks it against upward motion, thereby maintaining the adjusted compression of the spring 18. This is true of all of the forms. When it is desired to release the compression of the spring 18, the operator presses the finger rest 26 on the free end of the lock arm 25, the locking shoulder 32 being thus disengaged from the sleeve 20 so that the spring 18 is enabled to function and the sleeve 20 elevated thereby. Under such conditions darning or the like may be readily accomplished. If slight spring pressure is desired for darning, this may be accomplished by depressing the knob 21 slightly. When normal stitching is required, further depression of the knob 21 to attain the desired compression in the spring 18 and the desired pressure upon the fabric under the presser foot 16 is quickly produced. Thus, it is apparent that any desired compression of the

spring 18 within the range from no compression at all to the maximum compression attainable may be immediately accomplished by the operator with very simple finger movements.

5 Since other modifications of the invention herein disclosed doubtless will suggest themselves to those skilled in the art to which this improvement pertains, it is intended to cover all variations falling within the scope of the claims.

10 We claim as our invention:

1. In means for varying the pressure imposed upon the presser foot of a sewing machine having a head, said foot being carried upon the lower end of a presser bar whose upper end is vertically movable in said head under the pressure of a spring thereon, the combination of: a member having a bore and adapted to be secured in the top of said head of said sewing machine; a stem mounted in said bore to slide vertically therein, said stem being adapted to telescope with said presser bar and be connected with the upper end of said spring to place the latter under compression; and a spring-actuated lock carried by said bored member and adjustably engaged with said stem to retain the latter at any of a plurality of intermediate positions of vertical adjustment and to place said spring under correspondingly adjustable compression.

2. A combination as in claim 1 wherein said lock comprises a spring-biased lock arm having one end attached to said bored member, the other end of said arm being adapted to be depressed to release said stem.

3. A combination as in claim 2 wherein the top of said stem projects above said member and is provided with means to depress said stem into any desired position of adjustment for engagement by said lock arm.

4. A combination as in claim 1 wherein the top of said stem projects above said member and is provided with means to depress said stem into any position of adjustment for engagement by said lock.

5. A combination as in claim 1 wherein said lock comprises an arm which provides a shoulder locking said stem against movement in one direction.

6. In means for varying the pressure imposed upon the presser foot of a sewing machine having a head, said foot being carried upon the lower end of a presser bar whose upper end is vertically movable in said head under the pressure of a spring thereon, the combination of: a retaining member adapted to be fixed upon said sewing machine head; a stem slidably carried by said member and adapted to place said spring under compression; and spring controlled lock means connecting said stem and said member to hold said stem in any set position of adjustment on said member.

7. A combination as in claim 6 wherein said lock means comprises a spring-actuated lock arm normally engaging said stem and automatically locking said stem in set position, said arm being manually shiftable to release said stem.

8. A combination as in claim 7 wherein said stem passes through an aperture in said arm providing a shoulder to bind upon said stem.

9. A combination as in claim 7 wherein said lock arm and the top of said stem are disposed above said retaining member whereby to be located in exposed position above said machine head when in operative relationship, said arm and the top of said stem providing means for manual depression.

10. A combination as in claim 5 wherein said lock means includes a lock arm and said retaining member is provided with a spring seat containing a spring operating on said lock arm to move the latter into stem locking position.

11. In means for varying the pressure imposed upon the presser foot of a sewing machine having a head, said foot being carried upon the lower end of a presser bar whose upper end is vertically movable in said head under the pressure of a spring thereon, the combination of: a retaining member provided with an axial, vertical bore and with a head at its upper end, said member being also provided with a short external thread for binding the headed member on the top of said machine head; a stem slidably mounted in said bore and having means at its top to be engaged for depressing said stem, and being adapted at its lower end for telescopically engaging the upper portion of said presser bar and being operatively engaged with said spring to vary the compression thereof; and a friction lock arm connected at one end with said retaining member and connected with said stem in engaging relationship to lock said stem by frictional engagement therewith.

12. A combination as in claim 11 wherein said lock arm is provided with an aperture through which said stem passes, edge portions of said aperture serving to bind said stem in adjusted position.

13. A combination as in claim 11 wherein the head of said retaining member is provided with a spring seat containing a spring bearing against said lock arm to move the same to stem-binding position.

14. A combination as in claim 11 wherein said one end of said lock arm is positioned in a retention opening in said retaining member.

15. A combination as in claim 14 wherein said retention opening is located in said head of said retaining member.

16. In means for varying the pressure imposed upon the presser foot of a sewing machine having a head, said foot being carried upon the lower end of a presser bar whose upper end is vertically movable in said head under the pressure of a spring thereon, the combination of: a retaining member adapted to be fixed upon said sewing machine head; a stem slidably carried by said member for slidable adjustment to a plurality of intermediate positions between the extremes of its slidable movement in opposite directions, to place said spring under correspondingly different compressions; and lock means movable between said stem and said retaining member and carried by one thereof for holding said stem set in any of said intermediate positions of adjustment.

17. A combination as in claim 16 wherein said retaining member is provided with means for detachably fixing said member on said sewing machine head.

18. A combination as in claim 16 wherein said lock means includes a movable arm providing shoulder means engaging upon said stem to hold the latter.

19. A combination as in claim 16 wherein said lock means comprises a movable arm carried by said retaining member and presenting a shoulder frictionally engaging the side of said stem to lock the latter against movement in one direction.
